CIGARETTE AND MATCH CASE

Howard L. Auten, Glen Ellyn, Ill.

Application October 3, 1945, Serial No. 619,941

5 Claims. (Cl. 206—38)

1

This invention relates to a cigarette and match case, and more particularly to a cigarette case equipped with a blister compartment adapted to receive a packet of matches.

Cigarette cases have heretofore been provided of the usual rectilinear form and which are made sufficiently large to receive matches. The chief difficulty with such structures is that they are too bulky for the service man or working man to carry in his pocket; they offer little protection against moisture; and they afford no means for securing the packet of matches in position while a match is being broken off and ignited. In fumbling about with a match or packet of matches, the matches are often dropped onto the wet ground and their value as matches lost. Further, in the striking of a single match under hurried conditions, often the entire packet is set off with disastrous results.

An object of the present invention is to provide a cigarette case which is as thin at its lower end portion, and which meets the narrowest part of the pocket, as the ordinary cigarette case which does not provide a space for matches, while at the same time providing a chamber for carrying a packet of matches. A further object is to equip a cigarette case with a match compartment so formed that it occupies substantially no more usable space within the pocket than the ordinary cigarette case, while at the same time providing a waterproof case. Yet another object is to provide a match case with means for continuously locking within the case a packet of matches, and in such a fashion that a match may be torn off and struck without removing it from the case. A further object is to provide means for latching a resilient cigarette case so that under trying conditions the cover cannot be released from the container and the cigarette spoiled. Another object is to provide a cigarette container with a closure that may be secured against either end of the container and which will support the striking surface of the match packet against an outer wall of the container, while at the same time shielding the heads of the matches within the closure. Other specific objects and advantages will appear as the specification proceeds.

The invention is illustrated in a preferred embodiment, by the accompanying drawing, in which—

Figure 1 is a perspective view of a cigarette and match case embodying my invention, Fig. 2, a view similar to Fig. 1 but showing the striking portion of the match packet supported outside the case; Fig. 3, a view similar to Fig. 1 but

2

showing the closure secured to the bottom portion of the container and supporting the striking surface of the match packet against the outside wall of the container; Fig. 4, a vertical sectional view of the structure shown in Fig. 1; Fig. 5, a view similar to Fig. 4 but showing a match packet supported within the case and showing also a reinforcing band about the lower edge portion of the closure; Fig. 6, a transverse sectional view, the section being taken as indicated at line 6 of Fig. 4; and Fig. 7, a perspective view of the closure member in inverted position.

In the illustration given, 10 designates a container formed of any suitable material. A plastic or resin-like material, which is resilient in character, has been found most satisfactory and is in common use today for cigarette cases. It will be understood, however, that other materials may be employed in the construction of the case. The upper portion of the case is reduced at 11 to receive the lower sealing portion of a closure member 12. If desired, the lower edge of the closure member 12 may be provided with a sealing band 13, as shown in Fig. 5, which strengthens the lower sealing edge of the closure member. The band 13 may be formed integrally with the closure 12 or may be formed of plastic material cemented to the closure.

The case is of general oblong shape, having wide front and rear walls and relatively narrow side walls and thus of a contour adapted to be received within the pocket. The front walls of the container 10 are pressed forwardly and inclined upwardly to form a blister wall 14 which is connected to the front wall by triangular side walls 15. The resulting compartment formed between the blister wall 14 and the packet of cigarettes 16 is generally V-shaped in cross section and adapted to receive the lower portion of a match packet 17. The blister compartment just described extends also into the closure member 12 by virtue of a forwardly-extending blister wall 18 provided by the closure 12. Thus, the walls 14 and 18, with their connecting side walls, provide together a continuous generally V-shaped blister compartment which conforms in contour generally to the match packet 17.

The match packet 17 is an old structure and one commonly employed for carrying matches. The packet comprises a series of matches 19 which are bound at their lower ends to a cover member 20. The cover member 20 extends about the lower ends of the matches and provides on the opposite side a roughened striking surface 21. The cover member 20 extends upwardly and forms

a bend or loop 22 and provides on the opposite side a front sheet 23 which may extend over the match heads to protect them, or which may, as shown in Fig. 5, be folded behind the matches. Since this form of match packet is well known, a further description is believed unnecessary.

In the carrying out of my invention, I prefer to secure the match packet within the case, and in such a manner that it can be used continuously without ever removing it from the case and until the last of the matches are used. Any suitable means for effecting this result may be employed. I prefer to secure a bar 24 across the blister compartment portion within the closure 12 and at a point where it easily engages the loop 22 of the packet. Such a bar is effective in retaining the packet securely within the closure, particularly when the packet is formed as illustrated in Fig. 5, and at the same time renders the matches readily accessible. Further, the removal of the closure leaves the top of the cigarette package entirely exposed and accessible.

In order to retain the closure securely upon the container 10 under trying conditions, I provide overlapping portions of the two members with latch devices which will automatically engage when the parts are brought together. In the illustration given, the front wall of the closure is provided with a recess 26 adapted to receive a boss or button 25 carried by the lower portion of the container. When the parts are pushed together, the boss 25 will slip into the recess 26, and the parts are thus firmly secured against disengagement. However, when it is desired to remove the cover, a slight pressure upon the front wall of the container 10 or blister wall 14 will disengage the recess 26 from the boss 25 and permit longitudinal separation of the members. It will be understood that the boss and recess may be reversed as to location, and further that other suitable forms of latching the two parts together may be employed. I prefer the latching arrangement shown because there is no interference with the water-tight seal afforded by the overlapping closure and container members.

In the operation of the structure, the match packet 17 is secured in position with the loop 22 engaging the bar 24, and the forward portion of the cover 23 folded behind the matches 19. When it is desired to obtain a cigarette and match, the closure is removed, a match torn off and struck against the surface 21 of the packet 17. As a safety precaution, the closure is pressed down to the position shown in Fig. 2, with the packet 17 on the outer side of the blister wall 14, as illustrated in Fig. 2. In this position, the match may be struck while the remaining match heads are entirely enclosed within the protecting closure 12. As an alternative, and further as a preferred method, the closure 12 may be moved to the position shown in Fig. 3, with the closure inverted and receiving a portion of the bottom of container 10. The bottom portion of container 10 is preferably slightly reduced in size so as to enable the closure 12 to be pressed securely upon such bottom portion. In this operation, the packet 17 falls naturally outside of the case, as illustrated in Fig. 3, and rests against the blister wall 14. Here again, the match may be struck on the surface 21 without danger of igniting the match heads which are concealed within the closure 12.

In either of the operations just described, it will be noted that the service man or other user

can hold the cigarette case in one hand, the entire structure being, in effect, an integral or unitary piece. This arrangement is extremely important when the user is moving under difficult conditions and where there is no surface provided for placing the matches or the separate container or cover thereon.

In the structure shown, the bar 24, as well as the entire match packet 17, serves as a brace against the cigarette package 16 and maintains it in a compact and rectangular shape. At the same time, the cover of the cigarette package provides a smooth wall against which the match packet 17 is easily drawn when the closure 12 is moved vertically to open the container.

In the illustration given, the wall 14 at its lower end is bent in sharply at an angle at 14^a to provide a seat against which the lower portion of the packet 17 may rest. If desired, the wall 14 may be straight and the bend at 14^a omitted.

When the case is carried within the pocket of the user, the blister compartment actually occupies no usable space because the lower part of the pocket is the narrowest portion and the lower portion of the case is no wider than the ordinary cigarette case. As the pocket enlarges, the V-shaped structure of the blister utilizes the additional space, and the form of case therefore does not appear any bulkier to the user than the ordinary case.

While in the foregoing specification, I have set forth a number of details as descriptive of one embodiment of the invention, it will be understood that such details may be varied widely by those skilled in the art without departing from the spirit of my invention, and claims appended hereto should be looked upon as definitive of the invention.

I claim:

1. A cigarette case comprising a container generally oblong in cross section, and a closure therefor, said container and closure having their walls extended on one side to form a blister compartment adapted to receive a folded packet of matches, and a bar carried by said closure and extending across said blister compartment and adapted to extend under the fold of said match packet.

2. A cigarette case adapted to receive a match packet of the type secured at one end to a folded cover and providing there a roughened striking surface, comprising a container generally oblong in cross section, a closure therefor, said container and closure having their walls extended on one side to form a blister compartment to receive said packet, and a bar carried by said closure in said blister compartment and extended under said folded cover.

3. A cigarette case adapted to receive a match packet of the type secured at one end to a folded cover and providing there a roughened striking surface, comprising a container generally oblong in cross section, a closure therefor, said container and closure having their walls extended on one side to form a blister compartment to receive said packet, and a bar carried by said closure in said blister compartment and extended under said folded cover, said closure permitting the extension of the striking surface of said packet outside the case while the match heads are still confined within the case.

4. A cigarette case adapted to receive a match packet of the type secured at one end to a folded cover and providing there a roughened striking surface, comprising a container generally oblong

in cross section, a closure therefor, said container and closure having their walls extended on one side to form a blister compartment to receive said packet, and a bar carried by said closure in said blister compartment and extended under said folded cover, said closure permitting the extension of the striking surface of said packet outside the case while the match heads are still confined within the case and engaging the top of said container.

5. A cigarette case adapted to receive a match packet of the type secured at one end to a folded cover and providing there a roughened striking surface, comprising a container generally oblong in cross section, a closure therefor, said container and closure having their walls extended on one side to form a blister compartment to receive said packet, and a bar carried by said closure in said blister compartment and extended under said folded cover, said closure permitting the extension of the striking surface of said packet outside the case while the match heads are still confined within the case and engaging the bottom of said container.
